UNITED STATES PATENT OFFICE.

AUGUST SCHILLING, OF SAN FRANCISCO, CALIFORNIA.

DESIGN FOR CAN FOR TEAS, &c.

Specification forming part of Design No. **11,392**, dated September 2, 1879; application filed August 4, 1879.
[Term of patent $3\frac{1}{2}$ years.]

To all whom it may concern:

Be it known that I, AUGUST SCHILLING, of the city and county of San Francisco, State of California, have originated and designed a Can for Teas and other Substances, of which the following is a full, clear, and exact description, reference being had to the accompanying drawing, making a part of this specification.

A represents the body of the can, which is cylindrical; and B, the top. The can I make quite tall. The top B of the can I make conical, and provide it with a screw-top, C. The conical top I make with three shoulders, *d e f*, in the manner of forming an ogee, and the

screw-top projects from the upper or smaller shoulder.

What I claim as my invention is—

A design for tin cans in which the body of the can is cylindrical, and the top conical, and provided with three shoulders or grooves, *d e f*, in the manner of an ogee, substantially as above described.

In witness whereof I have hereunto set my hand and seal.

A. SCHILLING. [L. s.]
